CLAIM

We claim the ornamental design for a wearable thermoregulation device, as shown and described.

DESCRIPTION

FIG. 1 is a front, top perspective view of a wearable thermoregulation device showing the new design;

FIG. 2 is a rear, top perspective view thereof;

FIG. 3 is a front, bottom perspective view thereof;

FIG. 4 is a front elevational view thereof;

FIG. 5 is a rear elevational view thereof;

FIG. 6 is a right side view thereof;

FIG. 7 is a left side view thereof;

FIG. 8 is a top plan view thereof; and,

FIG. 9 is a bottom plan view thereof.

The broken lines depict portions of the wearable thermoregulation device that form no part of the claimed design.
